CLAIM

The ornamental design for a brassiere, as shown and described.

DESCRIPTION

FIG. 1 is a front perspective view of a brassiere according to my new and ornamental design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a front view thereof showing the brassiere in an alternate position; and,

FIG. 9 is a back view of the brassiere in the alternate position of FIG. 8.

In FIGS. 1-9, the broken lines at the underarms and at the shoulder straps that separate the front of the brassiere from the back of the brassiere represent the bounds of the claimed design while all other broken lines are directed to environment and are for illustrative purposes only; the broken lines form no part of the claimed design.
